CLAIM

The ornamental design for a vanity, as shown and described.

DESCRIPTION

FIG. 1 is a front right perspective view of a first preferred embodiment of a vanity in accordance with our new design; FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevational view thereof, with the left side being a mirror image;

FIG. 7 is a front right perspective view of a second preferred embodiment of a vanity with a filler strip in accordance with our new design;

FIG. 8 is a front elevation view thereof;

FIG. 9 is a rear elevation view thereof;

FIG. 10 is a top plan view thereof;

FIG. 11 is a bottom plan view thereof; and,

FIG. 12 is a right side elevation view thereof.
